C. D. VEST

SIGN SUPPORT

Original Filed March 28, 1922

INVENTOR.
C. D. VEST.
BY
Victor J. Evans
ATTORNEY.

UNITED STATES PATENT OFFICE.

CLARENCE DALE VEST, OF STOCKTON, CALIFORNIA.

SIGN SUPPORT.

Application filed March 28, 1922, Serial No. 547,593. Renewed May 15, 1923.

To all whom it may concern:

Be it known that I, CLARENCE DALE VEST, a citizen of the United States, residing at Stockton, in the county of San Joaquin and

5 State of California, have invented new and useful Improvements in Sign Supports, of which the following is a specification.

This invention relates to improvements in street signs and particularly to that type of 10 sign which is commonly used upon the street or sidewalk in front of buildings.

The principal object of this invention is to construct a sign which may be placed upon a sidewalk or any convenient location, 15 and one which will have a tilting and rocking movement imparted to a portion thereof by the action of the elements thereon, for instance the wind, which movement will attract the eye of the passerby.

20 Another object of this invention is to produce a device of the character described which will have the maximum movement without the possibility of becoming overturned.

25 Another object of this invention is to produce a sign of this kind which will be simple to construct, ornamental and readily adapted to any line of business, strong, durable and highly serviceable as an advertising medium.

Other objects and advantages will be apparent during the course of the following description.

In the accompanying drawings forming a 30 part of this specification, and in which like numerals are employed to designate like parts throughout the same.

Fig. 1 is a side elevation of my device as a whole,

40 Fig. 2 is a cross section taken on the line 2—2 of Fig. 1.

Fig. 3 is a cross section taken on the line 3—3 of Fig. 1, and

45 Fig. 4 is a modified form of reenforcing.

It is a well known fact that a sign that has a slight movement will attract the eye of a person where a stationary sign would be passed without observing. It is to produce a sign which will be acted upon as by 50 wind which will cause movement and thereby will be attractive.

In the accompanying drawings wherein for the purpose of illustration is shown a preferred embodiment of my invention, the 55 numeral 5 designates a metallic base portion

having a tapered surface and provided with a bead 6. A plate 7 is secured within the base 5 and is adapted to contact the interior of the base at a point slightly below the bead 6. This base 5 is filled with concrete 60 or other solid substance as shown at 8, and a chamber 9 is formed therein. At 11 I have shown a bowl shaped member having a spider 12 secured therein. This spider is adapted to centrally position a tubular 65 shaped member 13 which member is adapted to maintain roller bearings 14 and 16. The bearing 14 being a thrust bearing and adapted to contact a plate 17 mounted upon a shaft 18. This shaft 18 has a race- 70 way 19 which raceway is adapted to contact the roller bearing 16. The interior of the bowl 11 is likewise filled with concrete or other heavy substance 20 and it will be noted that this bowl has a contour 75 constructed on a greater arc than its sides thereby producing a portion which contacts with a plate 7 on a much finer curvature than the other portions of the bowl. A lug 21 extends through an opening 22 in the 80 plate 7 and is adapted to have suspended therefrom as by links 23 a counter weight 24. Mounted upon the upper portion of the shaft 18 are sign display wings 26, 27 and 28. These wings may be in conventional 85 shape, their purpose being to maintain advertising information. Referring to Figure 4 it will be noted that the entire spider is made of concrete. This modified form can be used in localities where they have little or 90 no breeze so that a very slight breeze would cause movement owing to the much more sensitive balance.

Assuming that the plates are assembled as shown in Figures 1 and 3 a breeze will 95 cause the bowl to rock upon the plate 7 and if the breeze is strong enough the side of the bowl 11 will contact the bead 6. At the same time the counter weight 4 will be moved upwardly and will at all times have a tendency 100 to return the bowl and its associated parts to their normal positions. The ball bearings will at the same time allow the wings 26 and 27 to revolve thereby bringing other signs into view.

105 It is to be understood that the form of my invention herewith shown and described is to be taken as a preferred example of the same, and that various changes in the shape, size and arrangement of parts may be re- 110

sorted to without departing from the spirit of the invention or the scope of the subjoined claim.

Having thus described my invention, I claim:—

In a device of the character described, the combination of a base, a plate mounted on said base, a filler mounted within said base and adapted to add weight thereto, a bead 10 formed upon the upper edge of said base, a

bowl adapted to rock on said plate and to contact said bead, a shaft rotatably secured to said bowl, display means carried on said shaft, said display means consisting of flat wing-like surfaces adapted to be contacted by a wind to cause a rocking motion of said bowl and means for returning said bowl to its normal position.

In testimony whereof I affix my signature.

CLARENCE DALE VEST.
